C. A. COYLE

TOOL BOX

Filed April 15, 1925

INVENTOR
Chas. A. Coyle
BY Frank D. Gray
ATTORNEY

UNITED STATES PATENT OFFICE.

CHARLES A. COYLE, OF PORT JEFFERSON, NEW YORK.

TOOL BOX.

Application filed April 15, 1925. Serial No. 23,250.

This invention relates to tool boxes and especially to receptacles for tools and other small articles used by auto-mechanics, though not by any means restricted to such use. Its object is to provide a device having a series of compartments divided into two sets having each a plurality of pockets or recesses of different depth but preferably uniform cross section.

10 A further object of my new and improved construction consists in the detachable means for spacing the said pockets by inserting between them cotter pins or other suitable spacers in a manner making it possible to 15 enlarge certain of the pockets by omitting certain dividing pins as may be desired.

These and other objects will appear from the following specification, pointed out in the appended claims and illustrated in the 20 accompanying drawings in which—

Figure 1 is a perspective view of the device;

Figure 2 is a vertical section of the same taken on the line 2—2 of Fig. 1;

25 Figure 3 is a detail view of one of the carrying plates;

Figures 4 and 5 are details of the partition plates and the cotter pin, and

Figure 6 is a view partly in plan of a 30 modification.

Referring to the drawings, the base of the structure is designated by the numeral 10, the same being a rectangular tray-like box or other form of receptacle of suitable size and 35 relative sides and ends usually formed of metal into which are inserted spaced metal plates 11 whose lower edges are the length of the inner length of the box 10, and whose ends are flanged at right angles at 13 for 40 riveting or otherwise securing to the inner face of the box flanges, and the lower edges are flanged outwardly at 14 and 15 for attachment to the bottom of the box.

The upper edges of the plates 11 are ordinarily parallel with the lower edges while the lateral edges 12 are inclined inwardly as illustrated. Vertical plates 16 are spaced apart in parallelism and mounted within the plates 11 and at right angles thereto. Their 50 bottom edges are flanged at 18 and thereby riveted or otherwise secured to the box bottom. The upper ends of these narrow plates are loosely connected by a handle member 17 for carrying purposes. These plates 16 55 may be securely fastened to the parts 11 by

ears 19 apertured at 20, bent inward and appropriately fixed to the parts as shown.

The space between the plates 11 is divided into the desired number of pockets or compartments by a series of plates 21 which, in the main or preferred form, are provided each with edges tubular in form as designated by 22, the partition plates 21 being of proper length to neatly fit between plates 11. The latter are accordingly provided with spaced 60 rows of apertures 25 each pair of which is vertically in alinement and separated the exact width of the partitions 21, so that the distance between the edges 22 of the partitions will equal that between the apertures 65 25 of a pair.

For the reason stated above, the partitions 21 may be readily positioned to bring the tubes 22 in registration with the apertures 25, whereby the cotter pins 23 may be 75 easily inserted through apertures and tubular edges to certainly position the partitions as desired. It is to be understood that any number of pins may be omitted from the apertures so that a corresponding number of 80 partitions may be dispensed with, to correspondingly enlarge the compartments remaining. In Fig. 1 is illustrated one enlarged compartment by omitting one cotter pin. Of course all the compartments may be 85 so enlarged, and the minimum space between the partitions of a given pocket may be determined by merely locating the apertures 25 accordingly.

As an alternative arrangement of the partitions, in Fig. 6 is shown in plan one end 90 of a box in which cotter pins are omitted and the vertical plates 11^a are provided with vertical slots on their inner faces in which the plain partition plates 21^a are guided as 95 shown. Any number of these partition plates may be omitted as in the other form. This form will result in outer projecting ridges 24, if the plates 11^a are bent to form the slots. In either case, the function of 100 determining the number and size of the compartments for receiving the tools used will be attained.

From the description above given it will be evident that the parts of my tool box may 105 be made of material of quite regular outline and smooth surfaces, that while the partition means are mounted on the vertical frame plates in regular order, if all pins or slots are utilized, yet without varying the 110

method of manufacturing the completed article, each user of the box may readily adapt the article to his immediate needs, including the particular tools that he desires to use. Further, the entire tool box may also be changed from time to time to suit varying conditions.

Nothing has been said thus far as to the spaces between the outer flanges of the base 10 and the vertical plates 11. These can of course be made serviceable as in all or most of the devices of this character, and need not therefore be especially emphasized in this specification. Also, it is to be understood 15 that applicant may readily make certain alterations in the details of the frame construction, or many of them without altering the general inventive idea of the device, and it is especially to be understood 20 that he claims all advantages accruing from the rule of equivalents.

What I claim, therefore, and desire to protect by Letters Patent, is,—

1. A tool box comprising a base portion 25 divided into compartments by vertical frame plates secured to the bottom of the box by their lower edges, supporting means for the box secured to the bottom of the box and extending above the frame plates, a 30 series of vertical partition plates mounted in spaced relation between the said frame plates, and means for detachably securing them to said frame plates.

2. In a tool box a base portion in the form 35 of a receptacle comprising vertical side and end walls, a pair of parallel, spaced frame plates mounted within said receptacle and at right angles to said end walls, handle means connecting the outer edges of the frame 40 plates for supporting the box, and partition plates held in spaced relation between said frame plates and disengageable therefrom.

3. In a tool box a base portion in the form 45 of a receptacle, a pair of parallel, spaced frame plates mounted within said receptacle and at right angles to its bottom, supporting plates secured by their edges to the frame plates, and detachable spacing means between said frame plates for partitioning the 50 space therebetween into compartments for receiving tools of different sizes.

4. A tool receptacle comprising a base portion including a bottom plate and upper 55 standing flanges therearound, a pair of spaced frame plates having their lower edges secured to said bottom plate and their upper edges having a row of apertures ex-

tending adjacent thereto, a pair of elongated plates positioned between said frame plates and secured to said bottom plate, partition 60 members having each a tubular edge fitting neatly transversely between the frame plates, and a series of pins adapted to be inserted between corresponding apertures of the frame plates and through the tubular 65 edge of the respective partition plates.

5. A tool box comprising a base portion divided into compartments by spaced frame plates secured to the bottom of the box by their lower edges, a pair of parallel plates 70 inserted transversely between the frame plates and secured to the latter in fixed position and to the bottom of the box by their lower edges, a handle member connecting the upper end of the intermediate plates, and means for adjustably dividing the space between the frame plates into compartments 75 or pockets adapted to receive tools of different sizes.

6. A tool box comprising a base portion 80 including a central compartment limited by spaced frame plates each having a row of apertures adjacent its upper edge and secured by its lower edge to the bottom of the box, a series of partition plates each having a tubular edge of a length equal to the distance between said frame plates, and pins inserted detachably in said apertures and through said tubular edges, whereby a plurality of pockets or compartments for tools 85 are provided between the said partition plates.

7. A tool box comprising a base portion divided into compartments by vertical, spaced plates secured to the bottom of the box by their lower edges, each said plate having two parallel rows of apertures parallel with the upper edges of the plates, the apertures of the lower row being in vertical alinement with those of the upper row, 100 a series of partition plates each having a pair of opposite tubular edges of a length equal to the distance between said plates secured to the box bottom, and being separated the distance between the apertures of said rows, and a series of pins adapted to be detachably inserted in said apertures and through said tubular edges, whereby a plurality of pockets or compartments are provided to receive tools of different sizes. 105

In testimony whereof I hereunto affix my signature.

CHARLES A. COYLE.
